UNITED STATES PATENT OFFICE

JOHN T. R. CONRAD, OF EAST CLEVELAND, OHIO

CAR-DOOR JACK

Application filed February 16, 1929. Serial No. 340,555.

This invention relates to new and useful improvements in car door jacks and aims to provide a device that is specifically adaptable for use in the opening and closing of car doors. 5 By reason of the present device railroads will save a considerable amount of money owing to the decrease of repaired doors and sides of box cars caused by forcing doors open and shut with a bar or other tool.

10 An important object of this invention is to provide a car door jack that comprises certain elements permanently associated with the two slide doors of the car as well as other separate elements adapted for association therewith to be manually operated whereby to cause the opening and closing of the doors and this in a relatively easy and rapid manner.

Furthermore the invention is characterized by its simplicity of construction and inexpensiveness of manufacture, the device consisting of relatively few parts being so correlated as to reduce the possibility of disarrangement to a minimum.

25 With the foregoing and other objects in view as the nature of the invention will be better understood, the same comprises the novel form, combination and arrangement of parts hereinafter more fully described, shown 30 in the accompanying drawings and claimed.

In the drawings wherein like reference characters designate corresponding parts throughout the several views:

Figure 1 is a fragmentary side elevation of a box car wherein the adjacent sliding doors are equipped with my improved jack to facilitate the proper and rapid opening of the doors,

40 Figure 2 is a detail longitudinal fragmentary section through the car taken above the device and looking downwardly thereon,

45 Figure 3 is an enlarged fragmentary elevation of the adjacent edges of the door and a longitudinal section through the gear box of the device, for more clearly illustrating the construction of the device and its association with the doors,

Figure 4 is a vertical section through the gear box of the device,

50 Figure 5 is a longitudinal vertical section

taken substantially upon the line 5—5 of Figure 4 looking inwardly toward the box,

Figure 6 is a perspective of the gear box, the cover unit being removed therefrom,

Figure 7 is a perspective of the sectional gear box cover,

Figure 8 is a top plan view of the spur gear unit mounted for rotation within the gear box,

Figure 9 is a top side perspective of one of the rack bars that comprise essential features of the present invention,

Figure 10 is a fragmentary side elevation of a modified form of rack bar, and

Figure 11 is a front side perspective of one of the tin carrying plate members associated with each of the sliding doors of the box car.

Now having particular reference to the drawings A designates generally a conventional box car while B designates the usual 70 sliding doors associated therewith.

In carrying out the present invention I provide a pair of metallic plates 5—5 adapted to be rigidly secured to the outer sides of the doors B—B adjacent the inner edges thereof, said plates being ranged one above the other as clearly illustrated in Figures 1 and 3.

Each plate 5 is formed centrally with an outwardly extending pin 6 as more clearly illustrated in Figure 11. The invention further consists of a gear casing 7 comprising an open sided boxing 8, the rear wall of which is formed centrally with a circular opening 9.

Adapted to be secured to the open front side of this boxing is a pair of cover sections 10—10, the adjacent edges of which are formed intermediate their upper and lower ends with rounded notches 11—11 to provide a circular opening of the cover as more clearly illustrated in Figure 5.

Extending through this opening and entering the opening 9 in the rear wall of the boxing 8 is a shaft 12, the outer end of which is provided with a relatively large hand wheel 13.

Within the casing, said shaft 12 is provided with a ratchet gear 14 while longitudinally slidable through the casing above and below this gear 14 are oppositely extending rack bars 15—15, the inner edges thereof be-

ing provided with rack teeth but have mesh with the ratchet gear 14, see Figures 3 and 4.

The ends of these racks bars 15—15 adjacent the pin carrying plate 5—5 are in each instance provided with an eye 16 for loose engagement over the adjacent pin 6 of the respective plate 5 associated with the doors of the box car.

Furthermore the opposite ends of said rack bars are provided at their inner surfaces with stop lugs 17—17 to limit the movement of the bars through the gear casing in their opening direction.

If desired the eyes of said rack bars 15 may be of oval shape as designated by the reference character 16' in Figure 10. Obviously therefore when the doors are closed as illustrated in Figure 1 the rack bars 15—15 are suspended outwardly so that the eye end thereof will be directed toward the gear casing.

These eyes of the bar are then arranged over the pins 6—6 and the wheel 13 then rotated obviously causing the movement of the rack bars and the same general method is employed in closing the doors B—B after the box car has been loaded.

It will thus be seen that I have provided a novel, simple and useful means for opening and closing the sliding doors of box cars and even though I have herein shown and described the invention as consisting of certain detail structural elements, it is nevertheless to be understood that minor changes may be made therein without affecting the spirit and scope of the appended claims.

Having thus described my invention, what I claim as new is:

1. In a box car jack of the character described, pin members permanently and rigidly associated with the sliding doors of the box car, a pair of reversely movable bar members having eyes at one of their ends whereby to facilitate their detachable association with said door pin and manually controlled means causing the reverse sliding movement of said bars with respect to each other after they have been attached to said pins.

2. In a detachable box car jack of the character described, a pair of rectangular anchoring plates having laterally extending pins constructed for rigid and stationary association with the sliding doors of the box car, a pair of reversely movable rigid bars having eyes at one of their ends for the reception of the pins in a manner to detachably mount said bars on said pins, and means for shifting said bars in reverse directions after same have been mounted on the pins of the anchoring plates.

3. In a detachable box car jack of the character described, a pair of pin members adapted for rigid and permanent mounting on the sliding doors of the box car, a pair of rack bars having eyes at one end for the reception

of the pins in a manner to detachably mount said rack bars thereon, a gear casing through which said rack bars are slideable, a manually rotatable rack gear within said casing in operative engagement with the rack bars whereby to cause the reverse longitudinal movement of the bars when said gear is rotated, and an actuating handle connected to the gear.

In testimony whereof I affix my signature.

JOHN T. R. CONRAD.
